UNITED STATES PATENT OFFICE.

WILLIAM R. MOWERY, OF BELLEVUE, OHIO.

DESIGN FOR A CURLING-IRON HEATER.

SPECIFICATION forming part of Design No. 31,124, dated July 4, 1899.

Application filed June 6, 1899. Serial No. 719,613. Term of patent 14 years.

To all whom it may concern:

Be it known that I, WILLIAM R. MOWERY, a citizen of the United States, residing at Bellevue, in the county of Huron, State of Ohio, have invented and produced a new and original Design for a Curling-Iron Heater, of which the following is a specification, reference being had to the accompanying drawing, forming part thereof.

10 The figure is a perspective view showing my new design.

As shown in the drawing, the leading or material feature of my design consists of a collar A, provided with curved prongs or supports B C and D D, disposed or arranged as shown in the figure. The said collar A is pro-

vided with outwardly and upwardly extending supports B C D D. The supports B and C differ from the supports D D and also from each other. The support B has on its upper end an eye or loop b, and the support C, immediately opposite, is provided on its upper end with a rest or open seat.

Having thus described my invention, what I claim as new, and desire to secure by Letters 25 Patent, is—

The design for a curling-iron heater, as herein shown and described.

WILLIAM R. MOWERY.
